(57) **CLAIM**

The ornamental design for an adhesive mount base, as shown and described.

DESCRIPTION

FIG. 1 is a front perspective view showing an adhesive mount base of the present invention;

FIG. 2 is a front view thereof;

FIG. 3 is a right side view thereof;

FIG. 4 is a top view thereof;

FIG. 5 is a bottom view thereof;

FIG. 6 is a left side view thereof; and,

FIG. 7 is rear view thereof.

In the drawings, the broken line showings are for purposes of illustrating environmental structure or portions of the adhesive mount base that form no part of the claimed design.
